Inventor:

Abel C. TALLMAN

United States Patent Office.

ABEL C. TALLMAN, OF PHILADELPHIA, PENNSYLVANIA.

Design No. 2,933, dated February 11, 1868.

DESIGN FOR A SKATE-RUNNER.

The Schedule referred to in these Letters Patent and making part of the same.

TO ALL WHOM IT MAY CONCERN:

Be it known that I, ABEL C. TALLMAN, of the city and county of Philadelphia, and State of Pennsylvania, have invented a new Design for a Skate-Runner, of which the following is a description, the design being shown in the accompanying drawings, which make part of this specification.

The design consists in the configuration of the inclinations and shape of the three standards, A B C, with the wave-formed points D E, the position and inclination of the three legs, *a b c*, indicating the curve of the foot-plate, to which they are to be attached.

By means of the shape and inclination of the standards A B C, the latter one of which is of a swan-neck design and form, a rakish, cutter-like appearance is given to the runners, the points D and E helping to give a wave-like appearance to the whole.

Of course I do not confine myself to the size of the runners, nor to the material of which they are constructed.

Having thus described my invention, what I claim as new, and desire to secure by Letters Patent, is—

The design of the configuration of a skate-runner, substantially as herein described and shown.

To the above I have signed my hand, this twentieth day of January, 1868.

ABEL C. TALLMAN.
